FASTENER FOR GARMENTS OF ELASTIC FABRIC

Leo Roseman, Newark, N. J.

Application May 4, 1935, Serial No. 19,830

9 Claims. (Cl. 2—265)

This invention relates to fasteners for use with elastic fabric and more particularly with fasteners for the edges of garments formed of elastic fabric, one object of the invention being to provide such a fastener embodying novel and improved features of construction so that the edges of the garment carrying the fastener may stretch to accommodate stretching of adjacent portions of the garment, and the fastener shall be practical, strong and durable.

For many years there has been great demand for elastic garments, and many efforts have been made to provide a satisfactory elastic fastener.

However, to my knowledge there have been no satisfactory fasteners for the closures of garments formed of elastic material because either the fasteners have been non-stretchable so as to defeat the purpose of the elastic garment and cause imperfect fit of the garment adjacent the closure, or discomfort to the wearer; or where the fastener elements have been applied to elastic tape, the fastener elements quickly become torn or detached from the tape by the constant stretching and resultant friction on the threads of the stitches adjacent the fastener elements which has caused breaking of the threads.

Another object of the invention is to provide a fastener of the character described wherein there shall be a minimum of stretching tension on the stitches which secure the fastener to the garment, or in other words to provide such a fastener wherein the elastic fabric of the garment may stretch substantially independently of the fasteners and the stitches which attach the fasteners to the elastic fabric.

A further object is to provide such a fastener wherein the fastener elements shall be directly secured to a strip of material which shall be non-elastic or have elasticity less than that of the elastic of which the garment is formed and said fastener strip shall be secured to the elastic garment by stitches penetrating the elastic garment and the fastener strip only at points closely adjacent the fastener elements, with a certain amount of free slack or puckering in the fastener strip between the adjacent fastener elements, so that the said slack or puckering in the fastener strip will permit stretching of the elastic fabric to an extent limited by the amount of said slack.

Another object is to provide a fastener for the closure of an elastic garment whereby the fastener will permit different degrees of elasticity at different portions of the closure, so that the closure may be made non-elastic, or of limited

elasticity, or of substantially unlimited elasticity, at different points in the length of the closure as may be desired for proper fitting of the garment and comfort to the wearer.

Other objects are to provide a fastener of the character described which shall be substantially concealed, which shall provide thinness or a minimum of bulkiness at the closure of the garment to which the fastener is applied, and which shall permit connection of the edges of the closure in edge to edge or abutting relation instead of in overlapping relation; and to obtain other advantages and results as will be brought out by the following description.

Referring to the accompanying drawings in which corresponding and like parts are designated throughout the several views by the same reference characters,

Figure 1 is a perspective view of a garment having a fastener embodying the invention applied thereto.

Figure 39 is a detached fragmentary perspective view of a modified form of the hook fastener element and

Figure 40 is a fragmentary sectional transverse view showing a modified manner of stitching the garment on the facing strip.

For the purpose of illustrating the principles of the invention I have shown it in connection with a corset A formed of elastic material which has a closure B to which the fastener of the 60 invention is applied. As shown, the garment is longitudinally stretchable, that is, may stretch from top to bottom, and the closure B is correspondingly stretchable to permit accurate fitting of the garment and ensure comfort to the 65 wearer.

One form of the fastener is shown in Figures 2 to 9 inclusive and includes a strip 1 of suitable fabric which may be thin elastic fabric or cloth cut on the bias so that the strip is longitudinally stretchable. As shown at 2 and 3 the edge portions of the strip are folded inwardly upon the main portion to make the strip of double thickness. This strip is secured to the edge of the elastic fabric or garment A by a line of 70 stitches 4 so formed that at predetermined points

in the line of stitches, gaps 5 are provided between the facing strip 1 and the garment edge to receive fastener elements 6. In stitching the facing strip to the garment edge, generally the garment edge will be laid flat on the strip during the stitching operation and then folded 5 backwardly over the stitches as shown in Figures 6 and 29 so that the stitches are concealed on the garment side of the fastener. The gaps 5 may be formed in any suitable way for example with a sewing machine which at predetermined intervals skips or slips a stitch or stitches, one such machine being shown in the copending application of Herman Rosenman and Leo Rosenman, Serial No. 17,160, filed April 19, 1935. 15

Arranged between the facing strip C and the edge of the garment A is a fastener strip or carrier D. This fastener strip is shown as composed of two superposed strips 7 of suitable material which is preferably non-stretchable or is 20 capable of very slight stretching. The fastener elements 6 are secured between two strips 7 by stitches 8. As shown the fastener elements are wire eyes having hook engaging portions 9 and base loops 10, and the stitches traverse the 25 wire of the eyes and pass through the base loops for securely fastening the eyes on the strips. The eyes are spaced longitudinally of the strips 7 at distances greater than the distances between the gaps 5 when the garment is unstretched so 30 that as the eyes are slipped through the gaps, slack is formed or the strip 7 is puckered between the adjacent eyes as indicated at 11. The fastener strip D is secured to the facing strip C and garment edge A only at points behind or in 35 close juxtaposition to the respective fastener elements. For this purpose, the strips 7 are formed with tabs or extensions 12 behind the fastener elements, and a line of stitches 13 is formed through the garment edge A, the tabs 12 and the facing strip C as shown in Figures 7 and 8.

With this construction, it will be observed that when the garment edge A is in stretched or in normal condition there will be slack or 45 puckering in the fastener strip D between the adjacent fastener elements as shown in Figures 5 and 7, and that upon stretching of the garment edge, the facing strip due to its elastic or bias structure may also stretch, and the slack or puckering in the fastener strip D permit the stretching of the garment and facing strip to the limit of the slack 11 in the fastener strip D as shown in Figures 5 and 8. At the same time, the fastener strip D will limit the stretching, 55 so that the facing strip will not be stretched beyond its limit of stretchability. This is particularly important where the strip is formed of bias fabric because if bias fabric is stretched beyond a certain point it will not retract to its initial non-stretched condition.

It will be understood by those skilled in the art, that one thread, usually the bobbin thread which is utilized to form the lines of stitches 4 and 13 will be elastic thread to permit the stretching of the elastic garment and facing strip, while the threads used for the line of stitches 8 on the fastener strip will be non-stretchable. It will also be observed that with this construction there will be substantially no stretching or tension upon the stitches 8 adjacent the fastener elements, so that there will be a minimum tendency to breaking of the stitches and tearing or dislodging of the fastener elements from the strip. Furthermore, the fastener strip and the main portions of the fas- 75

tener elements are concealed by the material of the garment and the facing strip C. The form of the fastener strip and the manner of securing it in position ensures against tilting of the fasteners and locates the points of connection of the fastener strip with the garment closely adjacent the points of strain on the fastener elements when they are embodied in a garment.

5 Also the stitches at opposite sides of the gaps 5 are relieved of strain.

10 It will also be observed that by varying the amount of excess material or slack between the fastener elements, the amount of stretching of the garment edge may be varied within different 15 limits. Another advantage of the particular form of the fastener strip D is that there is a minimum of material therein, especially between the fastener elements so that the closure will be thin and have minimum bulk.

20 The fastener will of course include a complementary hook structure for the edge of the garment opposite that to which the eye fastener is secured, as shown in Figures 2, 3, and 4. The hook fastener will be substantially the same in 25 construction as the eye fastener, the main difference being that the facing strip E of the hook fastener 15 will not project beyond the hook as does the facing strip C project beyond the eye 6.

25 A modification of the invention is shown in Figure 11 wherein the fastener is similar to that shown in Figures 6 to 8, one difference being 30 that the fastener strip F has the tabs 16 arranged at the side of the strip opposite that from which projects the tabs 12 of Figure 6, and the fastener elements 17 are secured to the tabs. In this form of the invention also, there is a 35 line of zigzag stitches 18 connecting the facing strip C and the garment edge A so that there are two stitches 19 at each side of each tab 16 to restrain lateral movement of the tabs in the 40 gaps. The fastener strip F is arranged between the garment edge A and facing strip C and is secured in position by a zigzag line of stitches 20 passing through both the garment and the facing strip and including offset or elongated 45 stitches 21 in juxtaposition to each fastener element and penetrating the fastener strip in addition to the garment and the facing strip. The construction and operation of this form of the invention is otherwise the same as that shown 50 in Figure 7.

55 A further modification is shown in Figure 13 where the fastener strip G has the portions 22 between the fastener elements extremely narrow and juxtaposed tabs 23 and 24 projecting from opposite sides of the portions 22. The fastener elements are connected to the tabs 23 which are arranged in the gaps between the 60 garment and facing strips, while the tabs 24 are secured to the facing strip and garment by stitches 25. The construction and operation of this form of the invention is otherwise the same as that shown in Figure 7.

65 Where it is desirable to permit stretching of the garment and facing strip without limitation by the fastener strip, I may use a construction such as shown in Figures 14 to 19 inclusive. Here each fastener element 26 is connected to a base piece 27 including two superposed pieces of material between which the fastener element 70 is arranged. The base pieces are arranged between the garment A and facing strip C and within the gaps 28 corresponding to the gaps 5; and the base pieces are secured in position by a line of stitches 29 extending longitudinally of 75 the facing strip and garment edge. In Figure 16

the fastener is shown unstretched, and with reference to Figure 18 it will be observed that the garment and facing strip C may be stretched to the limits of their elasticity without any limitations by the fastener elements.

80 Figures 15, 17, and 19 correspond respectively to Figures 14, 16, and 18 but illustrate the hook fastener instead of the eye fastener. The structure is in general the same as that shown in Figures 14, 16, and 18, each hook 30 being connected to a base piece 31, and the base pieces being arranged between the facing strip E and the garment edge A as shown in Figure 4, with the shank and bill of the hook projecting from the edge of the garment and facing strip.

85 For convenience in handling the fastener elements attached to the base pieces as shown in Figure 14, and for easily and accurately locating the fastener elements in the gaps and preventing tilting or twisting of the fastener elements as 90 they are inserted, the base pieces 27 may be secured as by gluing to a tearable supporting strip 32 which may be for example of paper. After the fastener elements and base pieces have been secured in position as shown in Figure 21, 95 stretching of the garment and facing strip will result in breaking or tearing of the carrier strip between the base pieces as shown at 33 in Figure 22, and thereafter the garment edge may be stretched to its limit without hindrance from 100 the fastener elements.

105 It is also possible to provide a fastener of the general character described which wholly prevents or limits stretching of the garment and facing strip, and a structure to accomplish this 110 purpose is shown in Figures 24 and 25 where the fastener elements 35 are secured to a fastener strip 36 formed of non-stretchable material of uniform width. The fastener strip 36 may be secured in position by a line of zigzag stitches 37 having elongated or offset stitches 38 in juxtaposition to each fastener element and passing through the garment, the fastener strip and the facing strip.

115 The forms of the invention shown in Figures 7, 16, and 25 may be combined in a single garment closure to provide different degrees of elasticity lengthwise of the closure. For example, as shown in Figure 26, a fastener strip like the strip D of Figure 7 may be secured between the 120 garment A and facing strip C at one point, while a fastener like the fastener 26, 27 of Figure 16 may be secured at another point in spaced relation to the fastener strip D, and the fastener strip of the type 36 shown in Figure 25 may be secured at another point in spaced relation to 125 the fastener 26, 27.

130 With such a construction, it will be observed that portions of the garment and facing strip which carry the fastener strip D will have a limited degree of elasticity, while the portions adjacent the fastener 26, 27 will be of unlimited elasticity, and the portions carrying the fastener 36 will be substantially non-stretchable. In all of the forms of the invention so far described the facing strip is shown as formed of bias cloth, while in Figures 27 and 28 the facing strip H is shown as formed of thin elastic fabric. This structure ensures less thickness of the fastener than the facing strip C, and to maintain a minimum of thickness and at the same time 135 avoid unraveling or fraying, of the edges of the elastic strip, the free edge may have a binding 38 secured thereon while the other edge may be overlapped by a line of zigzag stitches 39 penetrating the garment and the elastic strip. 140

It will be understood that the facing strip H may be combined with any of the forms of fastener strip hereinbefore described, the specific forms of fastener strips shown in Figures 27 and 28 being simply for the purpose of illustrating one type of fastener strip.

Figures 31 to 34 show a further modification of the invention wherein the eye fastener elements 41 are arranged to project directly from the edge of the garment. In this form of the invention the garment is designated I while the facing strip is designated K. The fastener strip designated L is of the same form illustrated in Figure 7 and is arranged with its edge substantially flush or in the same plane with the edge of the garment. The facing strip K has one edge stitched to the edge of the garment by a line of stitches 42 and is formed with slots 43 through which the fastener elements 41 project, the facing strip being folded around the edge of the garment and the fastener strip L and then secured to the opposite side of the garment by a line of stitches 43. The fastener strip L is secured in position by a line of stitches 25 44 passing through the tabs 45 of the fastener strip in the same manner that the stitches 13 of Figure 7 pass through the tabs 12. The construction and operation of this form of the fastener is otherwise the same as that of Figure 7.

In Figures 35 and 38 is shown a hook fastener embodying the same general construction as the eye fastener shown in Figures 31 to 34 inclusive. The main difference between this structure and the eye structure is that the hooks 35 45 are substituted for the eyes 41.

A modification of the hook fastener element is shown in Figure 39 wherein the end bar 47 of the base loop of the hook is secured to the edge of the base piece 48 and the major portion of 40 the hook projects beyond the base piece. With this form of the hook structure, the forward bar 49 of the hook base would be arranged in the gap 50 and this would provide less thickness adjacent the edge of the hook fastener which is 45 particularly desirable in a hook fastener in order to ensure adequate clearance for the eye between the bill of the hook and the fabric and avoid undue protuberance in the vicinity of the hooks.

In some cases, the carrier strip may be made 50 elastically stretchable between the points of attachment thereof to the garment; for example the strip 32 of Figure 20 might be thin elastic and have the base pieces or carriers 27 stitched thereon, so that the elasticity of the strip would 55 have the same effect as the extensibility of the slack 11 in Figure 6.

In Figures 2, 3, and 29 the stitches 4 are shown as passing through only the turned under edge 51 of the garment, but if desired, and especially 60 in connection with the hook fastener the stitches may pass through all of the plies as indicated at 52 in Figure 40 so as to provide compactness and avoid looseness of the material adjacent the engaging portion of the fastener element, hook 65 or eye.

In all forms of the eye fastener, the face strip provides a flap beneath the engaging portions of the eyes, as shown at M in Figures 2-4 inclusive and Figure 7, while in the hook fastener 70 especially as shown in Figure 40, the garment edge forms a narrow flap N over the hooks, and these flaps M and N cover the hook and eyes when they are engaged to prevent contact thereof with the body or underwear and provide a 75 neat appearance.

To facilitate initial application to the garment of the carrier strip of the type shown in Figures 7 to 12, the strip may be glued on a breakable non-elastic strip, for example of paper, at points adjacent the fastener elements with the fastener elements accurately spaced to enter the respective gaps and with the required slack between the fastener elements so that the carrier strip will be gripped by the feed mechanism when the garment and the carrier strip are fed through a sewing machine to stitch the carrier to the garment, and thereby hold the carrier against displacement. Upon first stretching of the garment the paper strip will tear whereupon the fastener will operate in the same way as the fastener of for example Figure 7.

If desired the face strips C, H, and K may be eliminated by folding over the edge of the garment, inserting the fastener strip between the plies of the fold, and perforating the fold to receive the fastener elements.

Other modifications in the details of structure of the fastener will occur to those skilled in the art as within the scope of the invention and therefore I do not desire to be understood as 25 limiting myself in the construction or use of the invention except as may be required by the following claims when construed in the light of the prior art.

Having thus described my invention, what I 30 claim is:

1. In a fastener, the combination with elastic fabric, of a fastener carrier strip extending in the direction of stretching of said fabric, and fasteners secured on said strip in spaced relation to each other, said carrier strip being secured on said elastic fabric only at points juxtaposed to said fasteners and with slack in the carrier strip between said points when the fabric is unstretched, whereby said slack will 40 permit stretching of said elastic fabric.

2. In a fastener, the combination with elastic fabric of a stretchable facing strip secured thereon to stretch in the same direction as said elastic fabric, there being gaps between said elastic fabric and said facing strip, a fastener carrier located between said elastic fabric and said facing strip and extending in the direction of stretch of said fabric and facing strip, and fasteners secured on said carrier in spaced relation 45 and each projecting through one of said gaps, said carrier being secured on said elastic fabric only at points juxtaposed to said fasteners and with slack in the carrier strip between said points when the fabric is unstretched, whereby 55 said slack will permit stretching of said elastic fabric.

3. The fastener set forth in claim 7 wherein said facing strip is secured to the elastic fabric by a line of stitches longitudinal of the strip and the gaps are formed by slipped, skipped or jump stitches, each gap has a plurality of stitches at each side extending transversely of the strip, and said carrier is a strip extending in the direction of stretching of the fabric and has a plurality of lateral tabs one arranged in each gap between said stitches and having a fastener element secured thereto, said carrier strip being secured to said fabric and said facing strip only at points juxtaposed to said tabs and with slack 60 between said tabs when the fabric is unstretched, whereby said slack will permit stretching of said elastic fabric.

4. In a fastener, the combination with elastic fabric, of a fastener carrier strip extending in 75

the direction of stretching of said fabric, and fasteners secured on said strip in spaced relation to each other, said carrier strip being secured to said fabric only at points in juxtaposition to said fastener elements and being extensible between said points to permit stretching of said elastic fabric.

5. The fastener set forth in claim 8 wherein said fastener carrier is a strip secured to said fabric only at spaced points in its length, and a fastener is secured to the carrier in juxtaposed relation to each of said points, said carrier strip being extensible between said points.

6. The fastener set forth in claim 7 wherein 15 said fastener carrier has relatively non-stretchable portions to which said fasteners are secured and has extensible portions between said non-stretchable portions, a continuous line of stitches penetrating the fabric and facing strip and the 20 non-stretchable portions of the carrier, said stitches clearing the remainder of the carrier.

7. In a fastener, the combination with elastic fabric, of a stretchable facing strip secured thereon to stretch in the same direction as said 25 elastic fabric, there being a row of gaps between said elastic fabric and said facing strip spaced in the direction of said stretching, a fastener carrier located between said elastic fabric and said facing strip and secured thereto to permit 30 stretching of the elastic fabric in said direction, and a fastener projecting through each of said

gaps and secured to said carrier and otherwise unconnected to said elastic fabric and facing strip.

8. In a fastener for use with elastic fabric, the combination of elastic fabric, a thin single 5 ply elastic facing strip secured thereon and stretchable in the same direction, a row of fasteners spaced apart in said direction of stretching, and a substantially non-stretchable fastener carrier located between said fabric and said strip 10 and secured thereto to permit stretching thereof in said direction, said fastener elements being secured to said carrier and otherwise unconnected to said fabric.

9. In a fastener for use with elastic fabric the 15 combination with elastic fabric, of a facing strip folded around and embracing the edge of said fabric and stretchable in the same direction as said fabric and having apertures adjacent and spaced longitudinally of the fold, a fastener carrier located between said fabric and said facing strip and secured thereto, and a fastener in each 20 said aperture and secured to said carrier independently of the attachment of the carrier to said fabric and facing strip, said fastener carrier 25 being a strip secured in position at only points juxtaposed to said fastener elements with slack between said points, whereby said slack will permit stretching of said fabric and facing strip.

30 LEO ROSEMAN.
